UNITED STATES PATENT OFFICE.

FRANK A. WELLS, OF CHICAGO, ILLINOIS.

WATER-CLOSET.

SPECIFICATION forming part of Letters Patent No. 351,236, dated October 19, 1886.

Application filed November 16, 1885. Serial No. 189,916. (No model.)

To all whom it may concern:

Be it known that I, FRANK A. WELLS, a citizen of the United States, residing at Chicago, in the county of Cook and State of Illinois, have invented a certain new and useful Improvement in Water-Closets, which is fully described in the following specification.

This invention relates to the so-called "siphon-closets," which are so constructed that the bowl is evacuated by the siphonic action of the discharge-pipe and refilled by the after-wash, the siphon being "broken" by the admission of air.

It relates particularly to those closets in which the air is exhausted from or rarefied in the longer limb of the siphonic discharge-pipe by means of the current of flushing-water, an air-pipe from the top or crest of the siphon being protruded into the flushing-pipe, so that the air is drawn from it by the passing current of water. A serious defect in these closets arises from the inadequacy of this means of effecting the exhaustion of the air from the siphon, and the sluggish movement of the contents of the bowl in the process of evacuation which results. Another serious defect is that the air thus drawn from the siphon is discharged with the flushing-water into the bowl and thence into the room, and this air, having been previously confined over the water in the trap, is invariably charged more or less highly with sewer-gas which has been first absorbed and then given off by the water in the trap—that is, passed through the water in the trap from the sewer beyond.

This invention is designed to cure these defects and at the same time provide means for thoroughly flushing the trap and the soil-pipe.

It comprises, in addition to the usual water-pipe discharging into the bowl for the purpose of flushing the same, another water-pipe discharging into the closet-discharge or soil-pipe beyond the siphon, and preferably, in order to accomplish a secondary purpose, into the trap between the siphon and the sewer and in the direction of the flow of water through the same, and an air-pipe from the crest of the siphon leading to and opening into this latter water-pipe, so that the exhaustion of air from the siphon is effected by the water-current through this latter pipe, which will carry the

foul air to a point such that it may escape through the ventilating-ducts provided for the sewer and its connections, rather than by the current of flushing-water through the flushing-pipe, which would discharge the foul air into the bowl, and thence into the room. 55

It comprises, further, a preferred form of construction of the air-pipe and water-pipes, whereby they are connected with the service-box in a single fitting, which may be made complete and adapted to be inserted into the bottom of any plain wooden or other service-box. 60

It comprises, also, a device by which the amount of the after-wash may be regulated in putting in such fitting, to correspond with the size of the bowl which it is designed to serve. 65

It comprises, also, a device for regulating the water-current, which operates to exhaust the siphon in such manner that the suction which said current causes may be increased or diminished, according to the exigencies of the case, and that the proportion of the contents of the service-box which passes by the flushing-pipe 75 and the said air-exhausting pipe may be varied as desired or found necessary. 70

In the drawings, Figure 1 is a vertical section of a tank service-box and closet, including my invention. Fig. 2 is an enlarged vertical section of the fitting by which the several pipes are connected to the service-box, showing the means of regulating the after-wash and the air-exhausting current. Fig. 3 is a plan of said fitting. 80 85

A is the bowl.

B is the siphon.

C is the trap.

D is the soil-pipe.

E is the flushing-pipe leading from the bottom of the service-box M to the flushing-rim A' of the bowl A. 90

E' is the siphon-exhausting water-pipe having the funnel-shaped mouth E' protruded up through the bottom of the service-box M such a distance that below the upper edge of said mouth the box M shall be sufficient to contain the necessary amount of water for the after-wash. Said pipe E' leads from the service-box to the aperture e', by which it opens into the portion C' of the trap C. 95 100

F is the air-pipe leading from the siphon B.

It penetrates the bottom of the service-box M, passes up alongside of the pipe E', and is bent into the goose-neck F', which is protruded downward into the funnel E¹⁰, and provided 5 therein with the inverted funnel - shaped mouth f'.

N is the tank of usual construction and having the usual appurtenances for controlling the supply of water thereto, and communicating 10 with the service-box M by a large opening, n', closed by the valve N', which is operated in any convenient and well-known manner, as by the pull-cord n², attached to the lever N², from which the chain or rod n²⁰ extends 15 to said valve.

For convenience of connecting the several pipes with the service-box, I provide the metal block P, which is preferably hollow, as shown, and has at the lower edge the flanges p p, provided 20 with the screw or bolt holes p' p', by means of which said block may be secured into the bottom of the service-box, an opening being cut to admit it. The thickness of this block or shell P should be about the usual 25 thickness of the plank or board which forms the bottom of the box, and it may be calked in, so as to make a water-tight junction with the box. The flushing - pipe E is inserted from below and soldered in at both upper and 30 lower surfaces of the shell P. The pipe E' is inserted from above. The opening which admits it through the upper plate of the shell P is plain, but that through the lower plate is screw-threaded, and said pipe has the 35 lower end of the upper section—i. e., the section which is thus inserted from above—externally screw-threaded, and being inserted through the plain opening in the upper plate it is screwed down through the lower plate, 40 and may be firmly secured by the set-nut p' on the lower side. The air-pipe F is inserted from above, and the pipe E' having first been set at such position as will leave the proper depth for the water for the after-wash, the 45 pipe F is brought down with its inverted funnel f' inside the funnel E¹⁰ and made concentric therewith, preferably by bringing it first into complete contact with the interior surface of the latter, and then screwing the latter up a distance equal to the amount of vertical separation necessary to leave the desired 50 annular aperture between said funnels, and while in this position the pipe F is soldered into the block P, both at top and bottom surface of the latter. The pipe E' may then be lowered until the desired annular aperture is obtained and the set-nut p' screwed up against the under surface of the block P. When the latter is hollow, as illustrated, a packing-washer, e', may be secured on its upper surface encircling the pipe E', to prevent the access of water to the interior of the shell P. Any subsequent adjustment of the size of the 55 aperture around the funnel f' is made by loosening the set-nut p' and screwing the pipe E' up or down, to diminish or increase said aperture. In order to prevent said adjustment

breaking loose or straining the pipe E', I provide the coupling E¹¹ long enough and internally threaded far enough to allow for all variation ever needed in said aperture. This coupling will be slipped onto the lower section of the pipe or the soldering-nipple E¹², which terminates above in the flange E¹³, before the lead section E¹⁴, which makes the junction with the bowl, is "wiped" on.

When the water is admitted to the service-box M, a part is passing out through the pipe E only while the service-box is filling up to the level of the mouth of the funnel E¹⁰, making a "fore-wash" of the bowl. After the water passes said height, a part passes through E' around the funnel f', and thereby draws air through pipe F from siphon B, producing a partial vacuum in the siphon and tends to induce its siphonic action, whereby the bowl is evacuated. The same water, passing on through the pipe E, is discharged through the aperture e² into the section C² of the trap C, and communicating motion to the water therein starts and drives it over into the soil-pipe D, thereby drawing the water from the portion of the trap back of the aperture e² and further increasing the siphonic action of the siphon B, and so hastening the movement of the contents of the bowl being discharged thereby. The air drawn from the siphon through the air-pipe F is carried over into the soil-pipe with the water from the pipe E', and is thus prevented from gaining access to the bowl and thence to the room. When the water in the service-box M has fallen below the level of the mouth of the pipe E', the water already in said pipe flows out and the current through said pipe ceases, and in consequence the siphonic action of the siphon B ceases, air being admitted to it through pipe F. The water remaining in the service-box below the level of the mouth of the pipe E' continues to flow out through the pipe E and enters the bowl, constituting an after-wash, which fills up the bowl to the level of the bridge of the siphon.

For convenience and compactness I prefer to make the lower portion of the pipe E' integral with the closet, being a duct, E¹⁴, in the metal or crockery-ware of which the closet and its siphon and traps are made, and it is so shown in the drawings; and in that case said duct terminates in a suitable nipple, to which the remainder of the pipe can be conveniently connected.

I do not find it essential that the water flowing through the pipe E' should discharge into the trap; but it may, though not with so perfect results as a means of producing suction 125 through the siphon, be made to discharge into the soil-pipe entirely beyond the siphon, as shown in the dotted lines e²⁰ in Fig. 1.

I claim—

1. In combination with the bowl, the siphonic evacuating-pipe and the trap between said pipe and the soil-pipe, the water-pipe E', discharging into the trap in the direction of the flow through the same toward the soil-pipe,

and the air-pipe leading from the siphon into the water-pipe E', substantially as and for the purpose set forth.

2. In combination with the bowl and the siphonic evacuating-pipe, the service-box, the water-pipe E', leading therefrom and having the funnel-shaped mouth E¹⁰, the air-pipe F, having its end protruded down into said funnel E¹⁰, said funnel being adjustable vertically to vary at will the annular water-aperture therein around the mouth of the air-pipe F, substantially as set forth.

3. The block or shell P, in combination with the pipes E and F, adapted to be secured therein, and the pipe E', vertically adjustable therein and having its upper mouth encircling the inverted mouth of the pipe F, all constructed substantially as described, whereby the entire

fitting may be applied to any plain service-box, for the purpose set forth. 20

4. In combination with the bowl and the service-box, the siphonic evacuating-pipe for the bowl and the discharge-pipe therefrom to the sewer, the water-pipe E', having its mouth in the service-box above the bottom and discharging into the discharge-pipe beyond the siphon, the air-pipe leading from the siphon into the said pipe E', and the flushing water-pipe E, having its receiving-mouth in the service-box below that of the pipe E', substantially 25 30 as set forth.
